CLAIM

The ornamental design for a closure, as shown and described.

DESCRIPTION

FIG. 1 is a perspective view of a closure showing our new design;

FIG. 2 is a top plan view thereof, the bottom being unornamented and not visible when the closure is installed on a container;

FIG. 3 is a front elevational view thereof;

FIG. 4 is a rear elevational view thereof;
FIG. 5 is a left side elevational view thereof;
FIG. 6 is a right side elevational view thereof;
FIG. 7 is a perspective view of an alternate embodiment
of the closure showing out new design;
FIG. 8 is a top plan view thereof, the bottom being

unornamented and not visible when the closure is in-
stalled on a container;
FIG. 9 is a front elevational view thereof;
FIG. 10 is a rear elevational view thereof;
FIG. 11 is a left side elevational view thereof; and,
FIG. 12 is a right side elevational view thereof.
